UNITED STATES PATENT OFFICE.

WILHELM KÖNEMANN, OF MINDEN, GERMANY.

WRITING-TABLE.

1,153,501.

Specification of Letters Patent. Patented Sept. 14, 1915.

Application filed September 23, 1911. Serial No. 650,995.

To all whom it may concern:

Be it known that I, WILHELM KÖNEMANN, a subject of the King of Prussia, residing at Minden, in the Kingdom of Prussia, Germany, have invented certain new and useful Improvements in Writing-Tables, of which the following is a specification.

This invention relates to writing tables which are constructed in such a manner that 10 the commonly flat table can be easily changed into an American desk, that is to say into a writing desk having a great many drawers, pigeon-holes, locked or unlocked compartments and the like. The part of the 15 writing table which contains said drawers pigeonholes and compartments is ordinarily below the plate of the table but it can be lifted so that it stands upon said plate by means of hand lever which actuates a system of articulated levers.

The improved writing table is particularly useful as a double desk.

In the accompanying drawings the improved writing table is shown by way of example with lifted chest of drawers.

Figure 1 is a front elevation of the improved writing table; Fig. 2 represents the writing table seen from behind, the back wall being removed.

30 The writing table has a chest of drawers *d* which is arranged in such a manner that it can be lowered into a hollow space so that its top plate is flush with the plate of the writing table. A hand lever *b* is mounted under the drawer *a* of the writing table on the front end of a horizontal axle *c*, the rear end of which axle carries a crank arm *e* to one end of which a push-rod *f* is pivotally mounted. The pivot bolt which connects the 35 push rod *f* with the crank arm *e* is guided in a vertical slot *m* of an iron plate *n*. On said pivot pin two levers *g*, *g* are pivotally mounted which have each a pin *o* projecting from the rear surface and engaging with inclined guide slots of an iron bar *p* fixed 40 upon said plate *n*. The outer ends of the levers *g*, *g* have horizontal arms *h*, *h* which carry the chest of drawers *d*. The free end of the hand lever *b* is slotted so that it can 45 be made to engage with a corresponding locking pin.

In order to lift the chest of drawers *d*

above the plate of the writing table, the hand lever *b* is turned from the position shown in Fig. 2 in dotted lines into the position shown in Fig. 1, whereby the pivot bolt is lifted in the vertical guide slot *m* of the iron plate *n* and the outer ends of the levers *g*, *g* with the horizontal arms *h*, *h* go up and lift the chest of drawers *d* which is 55 maintained in this lifted position without the aid of any locking means, as the push rod *f* is at the dead point position and a certain force is required to move the lever system in opposite direction.

60 I claim:—

1. In combination with a writing desk, a movable chest of drawers normally sunk below the top of the desk, two one-armed levers crossing each other and carrying upon 70 their free ends the said chest of drawers, movable pivots for said levers, a pivot common to said two levers, a crank handle pivotally mounted at the writing desk, a pusher rod connected with said crank handle 75 and with said pivot common to said two levers respectively, and a vertical guide for said pivot, substantially as described and shown and for the purpose set forth.

2. In combination with a writing desk, a 80 movable chest of drawers normally sunk below the top of the desk, two one-armed levers crossing each other and carrying upon their free ends the said chest of drawers, movable pivots for said levers, a pivot common to 85 said two levers, a crank handle pivotally mounted at the writing desk, a pusher rod connected with said crank handle and with said pivot common to said two levers respectively, and a vertical guide for 90 said pivot having two lateral slots in which the movable pivots of the levers are guided, substantially as described and shown and for the purpose set forth.

3. In combination with a writing desk, a 95 movable chest of drawers normally sunk below the top of the desk, two one-armed levers crossing each other and carrying upon their free ends the said chest of drawers, movable pivots for said levers, a pivot common to 100 said two levers, a crank handle pivotally mounted at the writing desk and that it locks the chest of drawers in the lifted position when it has been brought to its dead

point position, a pusher rod connected with said crank handle and with said pivot common to said two levers respectively, and a vertical guide for said pivot, substantially as 5 described and shown and for the purpose set forth.

In witness whereof I have hereunto set my hand in the presence of two witnesses.

WILHELM KÖNEMANN.

Witnesses:

FRIEDRICH TIEMANN,

WILHELM STRUP.
